UNITED STATES PATENT OFFICE.

JAMES A. WOTTON, OF ATLANTA, GEORGIA, ASSIGNOR TO WOTTON ELECTRIC & MANUFACTURING COMPANY, A CORPORATION OF GEORGIA.

AUTOMATIC ANNUNCIATOR.

SPECIFICATION forming part of Letters Patent No. 699,275, dated May 6, 1902.

Application filed June 10, 1901. Serial No. 63,919. (No model.)

To all whom it may concern:

Be it known that I, JAMES A. WOTTON, a citizen of the United States, residing at Atlanta, in the county of Fulton and State of Georgia, have invented certain new and useful Improvements in Automatic Annunciators; and I do hereby declare the following to be a full, clear, and exact description of the invention, such as will enable others skilled in the art to which it appertains to make and use the same.

My invention relates to improvements in mechanism for automatically resetting annunciators; and it consists in a solenoid provided with a divided core, one portion thereof being longer than the other portion, the shorter portion of which is connected with the mechanism of an annunciator and the longer portion of which is adapted by its momentum when moved in the coil of the solenoid to momentarily actuate the said shorter portion and accomplish the resetting operation.

It also consists in certain other novel constructions, combinations, and arrangements of parts, as will be hereinafter fully described and claimed.

In the accompanying drawings, Figure 1 represents a rear elevation of an annunciator, showing the improved resetting mechanism arranged therein. Fig. 2 is a front elevation of the face-plate of the annunciator, showing the needles or pointers mounted thereon. Fig. 3 is a detail rear elevation of the resetting-slide mounted inside the face-plate. Fig. 4 is a vertical central section through the face-plate and the pointers mounted thereon, some of the coils and magnets for moving the pointers being shown in side elevation. Fig. 5 is a vertical transverse section through the central portion of the annunciator, taken on a line of one set of magnets which are employed for operating the pointers of the annunciator. Fig. 6 is a detail view, partially in section and partially in elevation, of the solenoid.

It is very desirable in many instances to use annunciators which are provided with a suitable means for automatically resetting the pointers or indicators whenever a new call is to be registered. By my invention I can pro-

duce a mechanism which is particularly well adapted for such a purpose.

While my invention is well adapted for use in annunciators of various kinds, I preferably employ the same in connection with an annunciator such as that described and claimed by me in an application for a patent filed by me upon even date herewith. I have therefore illustrated in the drawings an annunciator of this kind and shown my improved resetting mechanism applied thereto.

The annunciator comprises a casing 1, in which a call-bell mechanism 2 is mounted, and an indicating face-plate 3, upon the rear side of which are mounted a series of magnets 4 4, which have poles projecting through the face-plate at the sides of indicating-pointers 5 5, which are pivotally mounted on the face of said plate. The pointers 5 5 are pivoted to studs or pins 6 6 on the face-plate and are provided with tangs or projections 7 7, which project through segmental recesses 8 8, formed in the face-plate. The pointers are adapted to be drawn to one side or the other, so as to direct the attention to one or the other of suitable indications on the face-plate, being attracted by the poles of the magnets 4 4. The pointers are preferably slightly magnetized, so that after the poles of the magnets have become demagnetized the pointers will be still held against the said poles, requiring a further mechanism and operation for returning them to their normal neutral positions. For positively resetting the pointers I mount a reciprocating slide 9 upon the rear face of the plate 3, the said slide having elongated slots 10 10 for engaging the pivot-pins 7 of the pointers. The said slots 10 10 are formed with flaring segmental end portions, as 11 11, which when the slide is in its lowered position coincide with the segmental slots 8 8 in the face-plate 3. The sides of these flaring portions 11 11 converge toward the elongated slots 10 10, so that when the slide is lifted the tangs of any of the pointers which may have been moved to one side will be brought to a vertical plane passing through the pivots of the said pointers, whereby the pointers will be positively brought back to their non-indicating positions. This slide 9

can of course be raised manually for resetting the pointers, and for this purpose a rod, as 12, is arranged to pass through the bottom of the annunciator and engage a horizontally-bent portion 13 of the slide, the said rod being provided with an operating knob or handle 14 at its lower end. In order, however, to reset the pointers automatically at the time each new call is made, I locate a solenoid 15 5 within the annunciator-casing and above the coils 4 and the slide 9. This solenoid is preferably a double one, being formed with two hollow cores 16 16, mounted on a suitable supporting base-plate 17, which is arranged with 10 in the annunciator. Extending through the hollow coils 16 16 are movable divided cores, the lower portion 18 of each core being made considerably longer than the upper portion 19 thereof. The lower cores 18 are secured 15 together by a cross-plate 20, while the upper cores 19 are connected by a plate 21. A rod 22 passes downwardly between the coils 16 16 and through apertures formed in the plates 21, 17, and 20. A nut 23 on the upper end of said rod 25 suspends the same from the plate 21. Below the plate 20 is a pair of tappet-nuts 23^a 23^b, suitably spaced apart and adapted to receive between them the bifurcated upper end 24 of the plate 9. It will be seen that by this construction if the upper plate 21 is raised the rod 22 will be lifted and the slide 9 also lifted to reset the pointers. In resetting the pointers of an annunciator by the impulse of a new call the releasing of the old pointers from 30 their magnets should be performed in such a manner as not to interfere with the setting of the pointer for the new call. When the solenoid is energized, the tendency of course will be to draw the cores to a central position 35 in the hollow cores. With the divided cores above described the lower, longer, and heavier portions 18 18 will be moved upwardly under the action of the coils 16, and they are made of sufficient size and length in proportion to 40 the parts 19 19 so that they will gain sufficient momentum to strike the short cores 19 19 and raise them, together with the rod 22 and the slide 9, to the limit of their motion, when the said long cores 18 18 will drop again 45 50 below the central positions in the coils which they strove to reach because of their gravity, their weight being sufficient to counterbalance the effect of the current passed through the coils 16 16 after the first impulse. It will 55 be seen that the pointers will thus be instantly reset upon the first impulse passing through the coils of the solenoid, while the current will be of long enough duration to set the pointer for the new call on the face-plate. 60 The wiring of the annunciator for the pointer-magnets and the bell-magnets is preferably arranged in the usual manner; but the current passing through the bell-magnet is preferably divided and a portion of it passed 65 through the coils 16 16 of the solenoid, this being accomplished by connecting the said coils 16 16 by wires 25 and 26 with the con-

tact-pieces 27 and 28, with which the bell-magnet 2 is connected through the wires 29 and 30. The wire 26 is also connected with 70 the common return-wire 31 of the pointer-magnets. The movement of the lower cores 18 18 and the plate 20, carried thereby, will have no effect upon the rod 22, except through the agency of the short cores 19 19 and the 75 upper plate 21, since the plate 20 loosely surrounds the said rod 22 and moves freely with respect to the same.

It will be evident that a solenoid of this character may be employed with other mechanisms beside that above described for resetting an annunciator wherever a similar movement is required, all within the spirit of the invention, and I do not, therefore, wish to be understood as limiting the use of my invention to the resetting of an annunciator. It will be seen that the automatic resetting of the pointers by the solenoid will not interfere with the manual operation of the slide 9 should it be desired to reset the pointers by 90 hand. It will be observed also that by the use of the above-described mechanism it is possible for two or more indications to show on the annunciator, because if while the two parts of the core are held together under the 95 action of the current a second or third or any number of other calls come in all will be registered. This is a valuable function of the device, producing improved results in mechanisms of this kind.

The mechanism will be seen to be exceedingly simple in its structure, easy to manufacture, and yet not likely to get out of order easily.

Having now described my invention, what 105 I claim as new, and desire to secure by Letters Patent, is—

1. A solenoid for imparting a momentary movement to reset annunciators or other similar mechanism, comprising a hollow coil and two cores extending into the opposite ends thereof, one of the said cores being longer and heavier than the other, and so arranged that when an electrical impulse is passed through the coil the larger core will be given an impulse, the momentum obtained thereby causing the said larger core to momentarily go beyond the point to which the current alone would move it so as to actuate the shorter core, the said larger core then being returned to the point out of engagement with the short core where it is held by the current until it is interrupted, substantially as described.

2. A solenoid for imparting movement to a suitable mechanism, comprising a pair of hollow coils, comparatively long connected cores extending into said coils, comparatively short connected cores also extending into said coils, the connection which joins said short coils being connected with the mechanism to be 125 operated, and means for sending an electrical impulse through the coils, the structure being such that the long cores will be drawn inwardly in the coils so as to gain sufficient mo-

mentum to carry them still farther so as to strike the short cores for actuating the mechanism connected therewith, after which the long cores will be separated from the other 5 cores by gravity, and will fall back to the point where the current holds them, the said long cores then dropping to their lowest position when the current is interrupted, substantially as described.

10 3. A mechanism for actuating a resetting device for annunciators, comprising a solenoid made up of a hollow coil, a divided core adapted to reciprocate therein one portion of the said core being connected with a reciprocating rod, a resetting-slide adapted to control the pointers of the annunciator and connected with the said rod and means for passing an electrical impulse through the coil of the solenoid whereby one portion of the divided core will be given a momentum which will carry it against the other portion of the core after which it will return to the point where the current holds it until the current is interrupted the reset mechanism being given 25 a momentary actuation, substantially as described.

4. In a resetting mechanism for annunciators the combination with a reciprocating pointer-controlling slide of a rod for lifting 30 the same, a solenoid made up of a pair of hollow coils, a pair of short cores connected with each other and with the lifting-rod, a pair of long cores connected with each other and extending well into the coils, and means for energizing the coils whereby the long cores will be drawn inwardly, gaining sufficient momentum to overcome gravity momentarily and strike the short cores and lift the annunciator-slide, after which they will fall back 35 40 out of engagement with the short cores to the point where the current holds them until said current is broken, substantially as described.

5. In a resetting mechanism for annunciators the combination with a reciprocating 45 slide adapted to positively release the point-

ers of the said annunciator, of a lifting-rod for operating the said slide, a solenoid provided with hollow coils arranged on either side of the said rod, divided cores extending into the opposite ends of the said coils, one pair 50 of cores being shorter than the other, a plate connecting the short cores and engaging the lifting-rod, a plate connecting the long cores and moving freely with respect to the said lifting-rod, and means for passing an electrical current through the coils whereby the long cores will be drawn inwardly so as to engage and lift the short cores and momentarily raise the lifting-rod, after which when the current is interrupted by releasing the push-button the said long cores will drop out of contact with the short cores because of the action of the force of gravity, substantially as described.

6. In combination with an annunciator, of 65 a reset mechanism therefor comprising a solenoid having hollow coils, divisible cores moving therein, one portion of each core being longer and heavier than the other portion thereof, a reset-slide adapted to return the 70 pointers of the annunciator to their normal positions, connected with the short portions of the said divided cores, suitable wiring for leading part of the call-bell current of the annunciator through the solenoid-coils, whereby upon the circuit being completed for a new call the energizing of the solenoid-coils will impart momentum to the long cores and force them momentarily against the short cores for actuating the reset-slide, the structure being 75 80 such that if other calls come in while the coils are energized, they will be indicated, substantially as described.

In testimony whereof I hereunto affix my signature in presence of two witnesses.
